Inventor

Frank P. Kober

UNITED STATES PATENT OFFICE.

FRANK P. KOBERT, OF AMITYVILLE, NEW YORK.

ELECTRIC RIVETING-MACHINE.

1,345,679.

Specification of Letters Patent.

Patented July 6, 1920.

Application filed September 29, 1917, Serial No. 193,905. Renewed November 14, 1919. Serial No. 338,113.

To all whom it may concern:

Be it known that I, FRANK P. KOBERT, a citizen of the United States, and residing at Amityville, in the county of Suffolk and State of New York, have invented certain new and useful Improvements in Electric Riveting-Machines, of which the following is a specification, such as will enable those skilled in the art to which it appertains to

make and use the same.

This invention relates to electric riveting machines, and particularly to machines of this class employing pneumatic, hydraulic or similar power for operating the working parts of the machine, and the object of my invention is to provide a simple, practical and efficient machine of the class and for the purpose specified, and a further object being to provide an electric heating apparatus for machines of the class specified, which is simple in construction and operation.

The invention is fully disclosed in the following specification, of which the accompanying drawings form a part, in which the separate parts of my improvement are designated by suitable reference characters in each of the views, and in which:

Figure 1 is a sectional side view of my improved machine;

Fig. 2 is a partial section on the line 2—2 of Fig. 1;

Fig. 3 is a section on the line 3—3 of Fig. 2 and on an enlarged scale;

Fig. 4 is a side view of a part of the machine shown in Fig. 1 with parts in a different position;

Fig. 5 is a partial section on the line 5—5 of Fig. 4;

Fig. 6 is a view similar to Fig. 5 with parts in a different position;

Fig. 7 is a partial section on the line 7—7 of Fig. 4 and on an enlarged scale;

Fig. 8 is a side view of a machine as shown in Fig. 1, but showing only a part of the construction and showing a modification;

Fig. 9 is a sectional side view of a part of the construction shown in Fig. 8 with parts in a different position; and,

Fig. 10 is a view looking in the direction of the arrow 10 of Fig. 8.

In Figs. 1 to 7 inclusive, I have indicated

at 11, the frame work of the machine which is U shaped in form and comprises a hollow back 12, a top arm 13, and bottom arm 14, said arms being hollow in construction, and provided at their ends with heads 15 and 15^a respectively. Mounted in the head 15 and vertically movable therein, is a plunger 16, with which is connected a toggle construction consisting of a bottom toggle lever 17, and top toggle lever 18, one end of which is pivoted to upwardly directed extensions 19 on the end of the arm 13 of the frame, the other end of said toggle lever 18 being pivoted to a toggle socket 20, with which the lower toggle lever 17 is also pivotally connected, said toggle socket being provided with a lever 21, which is pivoted to one end of a piston rod 22, the other end of which is pivotally mounted in a piston 23, movable longitudinally of a cylinder 24 by means of air under pressure introduced into said cylinder through a port or passage 25, and a valve device 26, and an air supply pipe 27, said valve device being controlled by an operating rod or lever 28. The cylinder 24 is mounted on the top portion of the frame 11 centrally thereof, and the lever 21 and toggle socket 20, are guided in the movement thereof by means of guide links 29, one of which is shown in Figs. 1 and 4.

Mounted in the head 15 of the arm 13 of the frame, is an electrode and plunger die holder 30, said holder being free to swing transversely of the arm 15 on a pin 31 secured in said arm. Mounted in and insulated from the holder 30, is an electrode 32 normally held in a raised position by means of a spring 33, said electrode being provided at its upper end with a head 34 provided with an insulated facing 35, and at its lower end with an enlarged tapered head 36. Mounted in said holder 30 at one side of the electrode, is a plunger die 37 normally held in a raised position by a spring 38. The upper end of the plunger die is provided with a head 39, and the lower end with an enlarged portion 40, having a recess 41 in the face thereof, and this construction is clearly shown in Figs. 1—2—3 and 5 to 7 inclusive.

In Fig. 7 of the drawing, I have clearly indicated means for operating the holder 30, which consists of a plate 42, pivoted to

the lower end of the pin 31, said plate being provided with oppositely directed arms, one of which is pivoted to a lug, formed centrally of the inner side of the holder 30, 5 as shown at 43, and with the other arm of which is pivotally connected a rod 44, having a hand piece 45. By means of this construction, the manipulation of the rod 44 by hand, will move the holder 30 into positions 10 to bring the electrode 32 and plunger die 37 successively into line with the plunger 16, and in this connection, it will be noted that the heads 34 and 39 on the upper ends of the electrode and plunger die respectively are 15 of the same dimensions as the diameter of the plunger, whereby on the descent of said plunger, the holder 30 is held in alinement and locked against movement, and it will be also noted that only when said heads are 20 brought into proper alinement with the plunger, the said plunger can be operated.

Mounted in the head 15^a, is a work piece supporting die 46, which extends through said head and provided with a reduced bottom threaded portion 47, on which is mounted a nut 48, and said die is hollow in form and construction, and adapted to receive a water pipe 49, having an inlet connection 50 and outlet connection 51, whereby said die, 25 which serves in the operation of the machine, as hereinafter described as an electrode, is water cooled. The upper or face portion of said die is provided with a recess 52, adapted to receive the head of rivet 30 blank 53, as clearly shown in Fig. 1.

Mounted in the hollow back portion 12 of the frame 11, is an electric transformer 54, having leads or conductors 55 and 56, said transformer being placed in connection with 40 any suitable source of electrical supply, by means of wires 57 and 58. The free end of the lead 55 is connected with a contact casing 59, which is hollow in form as indicated at 60, and with which the head 36 of the 45 electrode 32 is connected by means of a nut 61 on said electrode, and connected with the contact casing 59 are water supply and exhaust pipes 62 and 63, whereby water may be passed through said casing to cool the 50 head 36 of said electrode.

The exhaust pipe 63 is adapted to coil around the lead 55, as shown at 64, to cool said lead and the end of said pipe is adapted to be connected with the transformer, as indicated at 65, and connected with the outlet connection 51, is a pipe 66, which is adapted to coil around the lead 56, as shown at 67, and the end thereof connected with the transformer, as shown at 68, 55 and the water passed through the pipes 63 and 66 and coils 64 and 67, is adapted to pass through the transformer 54 to cool same, and discharged therefrom by a pipe 69 which passes through the back portion

of the frame 11, as clearly indicated in Fig. 1.

Connected with the free end of the lead 56, is a contact member 70, which is clamped or otherwise held in engagement with the shank of the die 46, as indicated in Fig. 70 1 of the drawing, whereby the current from the transformer is adapted to pass through the lead 56, contact member 70 to the die 46, as readily understood. Mounted on the die 46 above the contact member 70, 75 is a magnetic coil 71, placed in connection with any suitable source of electrical supply, by means of wires 72, whereby the die 46 may be magnetized and serve to hold the plates 73 in firm contact with the head of 80 the rivet blank 53 in the operation of connecting the same by said rivet blank as hereinafter described.

My improved machine or apparatus may be used as a portable machine, which is suspended from a crane in the usual manner, said crane having a depending chain or chains not shown, said chains being provided at the lower end thereof with a hook-shaped member 74, which is adapted to be 90 connected with a bale 75, pivoted to the frame, as indicated at 76 in Fig. 1, in which position the frame or machine will be truly balanced, but my invention is not limited to this form of mounting or supporting the 95 machine, as the same may be mounted on a floor or bedplate in the position, shown in Fig. 1, or a position at right angles to that shown in Fig. 1, in the manner of other machines of the class to which this invention 100 relates.

The operation of the machine as shown in Figs. 1 to 7 inclusive can be readily understood by all those skilled in the art to which this invention pertains when taken in connection with the foregoing description and the following statement thereof.

The position of the parts, as shown in Figs. 1—2—3 and 7, is the normal position thereof, in which the electrode 32 is in alinement with the plunger 16, and said electrode and the plunger die 37 are in their raised positions, it being understood that the work-piece consisting of the plates 73 with the rivet blank 53 passed therethrough, is supported on the die 46, as shown in Figs. 1—4—5 and 6. The first operation is to move the electrode 32, in contact with the protruding end of the rivet blank 53, which is accomplished by moving the lever 28 to 110 admit air from a compression tank not shown into the cylinder 24, to move the piston 23 longitudinally thereof, which operation operates the toggle levers 17 and 18, to depress the plunger 16 until said electrode 115 is in contact with said rivet blank, in which position it is held until said rivet blank is heated to the desired extent after which said

lever 28 is operated to shut off the supply of air, which permits the movement of the plunger into its normal position, and the electrode 32 into its normal position by the 5 spring 33, after which the electrode and plunger die holder are swung into the position shown in Fig. 6, and indicated in dotted lines in Fig. 7 by manipulating the rod 44 by hand as hereinbefore described, which 10 movement of said holder is guided by an enlarged head portion 77 on the lower end of the head 15, which enlarged head portion is clearly shown in Figs. 2—3—5—6 and 7, and this operation brings the plunger die 37 in 15 alinement with the plunger 16, after which the lever 28 is again manipulated to admit air into the cylinder 24, to operate the piston 23 and toggle levers 17 and 18, to depress the plunger 16, which operation moves 20 the plunger die 37 into engagement with the protruding end of the heated rivet blank 53 to fashion or head the same, as indicated in Fig. 6, after which the lever 28 is again manipulated to shut off the supply of the air 25 to the cylinder 24, to permit the movement of the plunger 16 back to its normal position, and the plunger die to its normal position, by the spring 38, after which the holder 30 is again swung on its pivot by 30 means of the rod 44 to bring the electrode 32 again in alinement with the electrode 16, it being understood that in both of the aforesaid movements of the holder 30, the plunger 16 must be in its raised position or the 35 lower end thereof above the top face of said holder.

The above completes one operation of the machine, or completes the formation of a head upon a rivet blank, and it will be 40 understood that this operation may be repeated as often as necessary or required to completely connect the plates 73, and in the repeated operation of the machine, the same is brought in its desired position by the 45 movement of the crane from which it is suspended, and the work piece or plates 73 are held stationary or mounted on a stationary support, but it will be understood that when my improved machine or apparatus is 50 mounted on a bedplate or stationary support, the work piece may be moved to bring it in the desired position to form or connect a rivet therewith.

In Figs. 8 to 10 inclusive, I have shown 55 a modification in which the arms 13 and 14 are of less transverse dimensions than those shown in Figs. 1 to 7 inclusive, and the electrode and plunger die holder is omitted, and the plunger die 37 is mounted directly in 60 connection with the plunger 16, as clearly shown in Fig. 9, and substituted for the electrode 32, is a hand operated electrode 78 substantially yoke-shaped in form, as indicated in Fig. 10, or provided with a handle

member 79, and guide member 80 which are 65 on opposite sides of the arm 13, said electrode being pivoted to said arm, as shown at 81, and the handle member 79 and guide member 80 are provided with elongated apertures 82, in which the pivot pin at 81 70 operates.

The electrode 78 is normally held in a raised position shown in Fig. 8, by a spring 83, and the base of said electrode is hollow in form, and is provided with laterally directed extensions 84 and 85, and the lead or conductor 55 is adapted to be connected with the extension 84 as shown, and connected with the top face of the extension 85, is an insulating pad 86, which is shown in Fig. 9, 80 and is adapted to operate in connection with the plunger die 37, as hereinafter described.

In this form of construction, the lower die 46 is the same as that shown in Figs. 1 to 7 inclusive, and forms one of the electrodes 85 of the heating apparatus. The normal position of the parts are shown in Fig. 8, and when it is desired to heat the rivet blank 53, passed through the plates 73, the electrode 78 is swung into the position shown 90 in Fig. 9 by hand, and held in such a position after which the lever 28 is operated to admit air into the cylinder 24, to operate the piston and toggle levers, as in the construction in Figs. 1 to 7 inclusive, to depress 95 the plunger 16 and plunger die 37 connected therewith, which operation will move the electrode 78 downwardly into engagement with the protruding end of the rivet blank 53, in which operation said electrode is 100 guided by the elongated apertures 82, and said electrode is held in such position by the air in the cylinder 24 until such rivet blank is heated to the desired extent, after which the air supply is shut off and the plunger 105 and plunger die returned to their normal positions, and said electrode to its normal position by the spring 83, after which the plunger die 37 is again depressed or moved downwardly by introducing air into the 110 cylinder 24, and the heated rivet blank 53 will be fashioned or heated in the manner shown in Fig. 6.

The construction shown in Figs. 8 to 10 inclusive of my improved electric apparatus, 115 may be connected with machines of the class specified without materially changing the form and construction thereof, and while I have shown certain details of construction for accomplishing the desired result, my 120 invention is not limited to such details as shown in the accompanying drawings, and changes therein and modifications thereof may be made within the scope of the appended claims without departing from the 125 spirit of my invention or sacrificing its advantages.

Having fully described my invention what

- I claim as new and desire to secure by Letters Patent, is:—
1. In a machine of the class described, a plunger, a plunger die operated by said plunger, an electric transformer, a work piece supporting die in electrical connection with said transformer, an electrode in electrical connection with said transformer and adapted to be moved into position between said plunger and a work piece mounted in said supporting die, and means for operating said plunger to move said electrode into contact with said work piece to heat the same prior to the operation of said plunger die on said work piece to fashion the same. 65
  2. In a machine of the class described, a plunger, a plunger die operated by said plunger, an electric transformer, a work piece supporting die in electrical connection with said transformer, an electrode in electrical connection with said transformer and adapted to be moved into position between said plunger and a work piece mounted in said supporting die, means for operating 70 said plunger to move said electrode into contact with said work piece to heat the same, and means for moving the plunger die into alinement with the heated work piece whereby the operation of the plunger will move 75 said die into engagement with said work piece to fashion the same. 80
  3. In a machine of the class described, a plunger, a plunger die operated by said plunger, an electric transformer, a work 85 piece supporting die in electrical connection with said transformer, an electrode in electrical connection with said transformer and adapted to be moved into position between said plunger and a work piece mounted in said supporting die, means for operating 90 said plunger to move said electrode into contact with said work piece to heat the same, and means for cooling said electrode and said supporting die. 95
  4. In a machine of the class described, a plunger, a plunger die operated by said plunger, an electric transformer, a work piece supporting die in electrical connection with said transformer, an electrode in 100 electrical connection with said transformer and adapted to be moved into position between said plunger and a work piece mounted in said supporting die, means for operating 105 said plunger to move said electrode into contact with said work piece to heat the same, and means for cooling said electrode and said supporting die. 110
  5. In a machine of the class described, a frame, a plunger mounted therein, an electrode and plunger die holder mounted to move transversely of said plunger, means for operating said holder to bring said electrode and plunger die successively into alinement with said plunger, said electrode being in electrical connection with said transformer, a work piece supporting die in electrical connection with said transformer, and means for operating 115 the plunger to bring said electrode and plunger die successively into contact with a work piece mounted in said supporting die. 120
  6. In a machine of the class described, a frame, a plunger mounted therein, an electric transformer, an electrode and plunger die holder mounted to move transversely of said plunger, means for operating said holder to bring said electrode and plunger die successively into alinement with said plunger, said electrode being in electrical connection with said transformer, a work piece supporting die in electrical connection with said transformer, and means for operating 125 the plunger to bring said electrode and plunger die successively into contact with a work piece mounted in said supporting die. 130
  7. In a machine of the class described, a frame, a plunger mounted therein, an electric transformer, an electrode and plunger die holder mounted to move transversely of said plunger, means for operating said holder to bring said electrode and plunger die successively into alinement with said plunger, said electrode being in electrical connection with said transformer, a work piece supporting die in electrical connection with said transformer, means for operating the plunger to bring said electrode and plunger die successively into contact with a work piece mounted in said supporting die, and means for magnetizing said supporting die to hold the work piece in firm contact therewith. 135
  8. In a machine of the class described, a frame, a plunger mounted therein, an electric transformer, an electrode and plunger die holder mounted to move transversely of said plunger, means for operating said holder to bring said electrode and plunger die successively into alinement with said plunger, said electrode being in electrical connection with said transformer, a work piece supporting die in electrical connection with said transformer, means for operating the plunger to bring said electrode and plunger die successively into contact with a work piece mounted in said supporting die, and means for magnetizing said supporting die to hold the work piece in firm contact therewith, and means for cooling 140 said electrode, supporting die and transformer. 145
  9. In an electric riveting apparatus, the combination with the plunger die and the work piece supporting die which forms one of the electrodes of the heating apparatus, of an electrode movable toward and from a work piece mounted in said supporting die by the means for operating the plunger die whereby said work piece may be heated prior to its fashioning by said plunger die. 150
  10. In an electric riveting apparatus, the

- combination with the plunger and plunger die, and the means for operating the same, and a work piece supporting die, of an electrode adapted to be moved into position between said plunger and a work piece mounted in said supporting die, whereby the operation of said plunger will move said electrode into contact with said work piece to heat the same prior to the fashioning there-
5 of by said plunger die.
11. In an electric riveting apparatus, the combination with a pneumatically operated plunger die of an electrode operated by said plunger die and adapted to heat a work piece prior to its fashioning by said die.
12. In a machine for heating metals electrically prior to shaping the same, the combination with a plunger die and work piece supporting die, of an electrode adapted to be moved into position between said dies, and means for moving said electrode and plunger die toward said supporting die to heat a work piece supported in said die.
13. In a machine for heating metals electrically prior to shaping the same, the combination with a plunger die and work piece supporting die, of an electrode adapted to be moved into position between said die, means for moving said electrode and plunger die toward said supporting die to heat a work piece supported in said die, and said plunger die being adapted to move toward the said heated work piece independent of said electrode to fashion the same.
14. In a machine of the class described, a U-shaped frame, a plunger mounted therein, a toggle mechanism for operating said plunger, means for operating said toggle mechanism, an electrode and plunger die holder movable transversely of said plunger, and means for operating said holder to bring said electrode and plunger die successively into line with said plunger.
15. In a machine of the class described, a frame, a plunger mounted therein, a toggle mechanism for operating said plunger, means for operating said toggle mechanism, an electrode and plunger die holder movable transversely of said plunger, a work piece supporting die mounted in said frame in line with said plunger, and means for placing said work piece supporting die and electrode in electrical connection with an electric transformer, whereby the work piece supported by said die may be heated by moving said electrode into contact therewith, and then fashioned by said plunger die.
16. In a machine of the class described, for riveting a plurality of parts together, a stationary die adapted to support a rivet blank, a heading die movable toward and from said stationary die, and electrical means for magnetizing said stationary die to hold said parts in firm contact with the head of said rivet blank in the operation of heading the same by said heading die.
17. In a machine of the class described for riveting a plurality of parts together, a stationary die adapted to support a rivet blank passed through said parts, a pneumatically operated electrode movable toward and from said rivet blank and adapted to heat the same, and a pneumatically operated plunger die adapted to be brought in contact with said heated rivet blank to head the same.
18. In a machine of the class described, a plunger, a plunger die operated by said plunger, an electric transformer, a work piece supporting die in electrical connection with said transformer, an electrode in electrical connection with said transformer and adapted to be moved into position between said plunger and a work piece mounted in said supporting die, means for operating said plunger to move said electrode into contact with said work piece to heat the same, means for moving the plunger die into alignment with the heated work piece whereby the operation of the plunger will move said die into engagement with said work piece to fashion the same, means for cooling said electrode and said supporting die, and means for cooling said transformer and the leads thereof.
19. In a machine for heating metals electrically, prior to shaping the same, the combination with a plunger die and a work piece supporting die of a hand operated electrode adapted to be moved into position between said dies, and means for operating the plunger die to move said electrode toward said operating die to heat a work piece supported in said dies.
20. In a machine for heating metals electrically prior to shaping the same, the combination with a plunger, of an electrode and plunger die operated by said plunger, a work piece supporting die, and means for operating said plunger to move said electrode and plunger die successively into contact with a work piece mounted in said supporting die to electrically heat and then fashion said work piece.
21. In an electric riveting apparatus, the combination with a work piece supporting die, of a pneumatically operated electrode brought into contact with a work piece supported in said die to heat the same, and a pneumatically operated plunger die independent of said electrode and adapted to be brought into contact with said heated work piece prior to fashioning the same.
22. In a machine of the class described, a stationary die adapted to support a work piece, an electrode movable toward and from said stationary die and adapted to heat the work piece supported therein, a heading

die movable toward and from said stationary die and adapted to fashion said heated work piece, and electrical means for magnetizing said stationary die to hold said 5 work piece in firm contact therewith in the operation of heating and fashioning the same.

In testimony that I claim the foregoing

as my invention I have signed my name in presence of the subscribing witnesses this 10
25th day of Sept., 1917.

FRANK P. KOBERT.
